Bonnets.

NANCY D. TERRY, OF PROVIDENCE, R. I.

Letters Patent for a Design No. 89, dated July 16, 1861.

SPECIFICATION.

TO ALL PERSONS TO WHOM THESE PRESENTS SHALL COME:

Be it known, that I, NANCY D. TERRY, of Providence, in the county of Providence and State of Rhode Island, have invented or produced a new and useful design, shape, or configuration, for a Shaker Bonnet; and I do hereby declare the same to be fully described in the following specification, and illustrated in the accompanying drawings, of which—

In constructing my improved bonnet, I make it of braided or woven strips of palm leaf or other like material, and form it in two parts, A B; A being the crown, and B the front or body, such body having its front edge bound with a band or fillet a, of a like material as that of which the body B is composed. It also has another band b, of such material, passing over the line of intersection of the body and crown, in manner as shown in the drawings.

Furthermore, I give to the upper part of the crown, or that portion of it above the line z z, a peculiar semi-elliptical shape, of the form shown in the drawings. From this line the inferior part of the said crown is contracted or formed at an angle of about 30 degrees, and the same is formed with three or more vertical plaita d d d, as shown in the drawings, the lower portion, or that part, which encompasses the neck, being bound with cloth or any other suitable material.

I claim my peculiar design, shape, or configuration for a shaker bonnet, the same being as above described and represented.

NANCY D. TERRY.
